TRACTION LINK FOR AUTOMOBILE TIRES

Rolf Pfoertner, 2176 E. 29th Ave., Vancouver 12,
British Columbia, Canada

Filed Mar. 13, 1972, Ser. No. 334,467

Term of patent 14 years

Int. Cl. D12—15

U.S. Cl. D12—154

The figure is a perspective view of a traction link for automobile tires showing my new design. The undisclosed side and end are mirror images of the side and end shown, while the undisclosed bottom is substantially flat and unornamented.

I claim:

The ornamental design for a traction link for automobile tires, as shown and described.
